Joseph Pratt, of Boston, Mass.
Assignor to

Bowers Pratt, & Co, of Boston aforesaid,

Letters Patent No. 544. Dated Jan 25th 1853.

numnum

The schedule referred to in these Letters Patent and making part of the same

numnumnum

To all persons to whom these presents shall come -

Be it known that I, Joseph Pratt, of Boston, in the County of Suffolk, and State of Massachusetts, have invented or produced a new and ornamental design or configuration of a cooking stove; and I do hereby declare that the same is fully represented in the accompanying drawings, and by the description herein after given.

The details or ornaments composing the general design whether on the legs, doors, or other parts, of the stove, are given in the said drawings with sufficient accuracy to enable a skillful pattern maker to readily comprehend the said design. The base plate, top plate, and hearth plate, are finished on their respective outer edges by a cyma reversa resting on a fillet which rests upon the crown of an inverted ovol. The cyma reversa is ornamented with leaf work as seen in the drawings, and both on the top plate and bottom plate it is surmounted by a fillet.

Des. 544

The ornamental character of each leg, principally consists of a shield in bas relief surrounded by sundry quirks or lesser ornaments of a character as shown in the drawings.

In the middle part of each of the doors there is a star pointed shield which is surrounded by a running fillet intermingled with lance heads and rose bud shaped ornaments on the latter in alto relief. The running fillet with its lance heads and rose bud shaped ornaments is also seen upon the ornamental projections that extend from the front plate of the stove and under the hearth plate. They are also seen in the projection over the largest door of the side plate Figure 1. The other parts of the design (not including in the same the word "Standard" as represented in Figure 2) consisting of the mouldings, projecting fillets, and panel work as seen in Figures 1, 2, and 3.

I claim the ornamental configuration or design substantially as represented in the drawings and as above described.

In testimony whereof I have hereto set my signature, this tenth day of August A.D. 1852.
